AUTOMATIC CANDELABRA

Filed April 9, 1949

UNITED STATES PATENT OFFICE

2,499,118

AUTOMATIC CANDELABRA

David G. Sipes, Struthers, Ohio

Application April 9, 1949, Serial No. 86,460

5 Claims. (Cl. 67—3)

1

This invention relates to candelabra and more particularly to candelabra which may be automatically lighted and extinguished as desired.

The principal object of the invention is the provision of candelabra incorporating means for automatically lighting and extinguishing a plurality of simulated candles.

A further object of the invention is the provision of candelabra incorporating wicks and fuel supply means therefor together with means for igniting the said wicks and extinguishing the same.

A still further object of the invention is the provision of candelabra having means for progressively lighting the various candles and progressively extinguishing the various candles.

A still further object of the invention is the provision of candelabra which may be lighted by remote control and extinguished by remote control.

The candelabra shown and described herein comprises an attractive and practical mechanism usable in various indicated places such as churches and the like in which candelabras are employed for aesthetic effect. It is well known that in lighting various candelabra as commonly used in churches, a definite arrangement of candles is provided and illuminated in a predetermined order and customarily extinguished in the same order.

The invention disclosed herein provides a device simulating a candelabra and candles therein and, in addition, provides for the automatic ignition of the candles on a predetermined pattern as well as the automatic extinguishment thereof when desired.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a plan view with parts broken away and parts in cross section illustrating the candelabra.

Figure 2 is a plan view of a portion of one of the simulated candles of the candelabra and including a mechanism for controlling the same.

Figure 3 is a plan view of a vacuum pump for 55

2

use in connection with candelabra shown in Figure 1.

By referring to the drawings and Figure 1 in particular it will be seen that a candelabra has been disclosed which comprises a main supporting stand 10 preferably tubular in nature and a cross piece 11 also tubular in nature and supported on the upper end of the main support stand 10 by means of a pair of supporting brackets 12 and 13, each of which is hollow and provided with removable closures 14 and 15, respectively. The cross piece 11 carries a plurality of simulated candles 16, each of which is provided with a removable conical tip 17 and each of which is of tubular formation and encloses a tube 18.

The simulated candles 16 are mounted on the tubular cross piece 11 as by brazing the same thereto to form an integral structure therewith and the tubes 18 communicate with the interior of the tubular cross piece 11. The tubes 18 terminate inwardly from the uppermost end of the simulated candles 16 and adjacent the tip 17 which is provided with a central orifice 19. A wick 20 is positioned in the orifice 19 and is enclosed in a wick tube 21 which is positioned partially within the tube 20 and which extends outwardly through the side thereof. An annular partition 22 is positioned about the tube 18 and registers with the interior of the simulated candles 16 to form a chamber 23 in which an oil supply may be carried. The lower end of the wick 20 is positioned in the chamber 23. It will thus be seen that upon the upper end of the wick 20 being ignited, the same will burn with the flame thereof corresponding with the candle flame of a real candle with respect to the simulated candle 16.

In order that the several wicks 20 can be ignited automatically from a remote location, an electrical igniter 24 is positioned in each of the simulated candles 16 and adjacent the wick 20 so that an electric spark can be directed therefrom to the tip 17 and the wick 20 ignited thereby. This arrangement is best illustrated in Figure 2 of the drawings wherein the electrical igniting means is shown in enlarged detail with respect to the remainder of the simulated candle 16. An electrical circuit is connected between the ignition means 24 and a control mechanism 25 which incorporates a timer 26, a suitable ignition coil and a control switch 27. A plurality of circuit wires 28 and 29 establish the electrical circuit with the igniter 24 and the timer 26 is a device known in the art and capable of predetermined operation

over a predetermined cycle. For example, in a candelabra holding ten candles, the timer 26 is arranged to ignite the candles in the following order: 1, 3, 10, 7, 6, 5, 8, 9, 4 and 2, which lighting arrangement is that customarily employed in the lighting of ten candle candelabras. It will be obvious that any other lighting arrangement may be employed if desired or that all the candles may be simultaneously ignited if desired.

In order that the candles may be extinguished when desired and from a remote location, a vacuum pump such as shown in Figure 3 of the drawings, and indicated by the numeral 30, is positioned in a remote location and connected by means of a suitable pipe 31 with the interior of the support member 10 which in turn communicates with the interior of the cross piece 11. A tubular slide valve 32 is disposed in the cross piece 11 and has a plurality of orifices 33 positioned thereon for simultaneous or progressive registry with the several tubes 18 in the simulated candles 16, as desired.

A solenoid 34 is positioned in one of the brackets 12 and a pair of circuit wires 35 and 36 connect the solenoid 34 with the timing mechanism 25 heretofore referred to. The plunger of the solenoid 34 is biased in one direction by a coil spring 37 and adapted to be moved in the other direction by the solenoid 34. As illustrated, the solenoid is energized and the slide valve 32 has moved to bring the several orifices 33 into registry with the tubes 18 whereby the same are placed in communication with the vacuum pump 30 and the flames on the wicks 20 extinguished by the inrushing air.

As heretofore described, the orifices 33 may be positioned progressively along the slide valve 32 so that as the solenoid 34 moves the same, the candles will be extinguished in a predetermined order.

It will be obvious to those skilled in the art that the cross piece 11 positioned horizontally in Figure 1 of the drawings may be alternately formed in two sections, each of which extend outwardly and downwardly with respect to the support member 10 and each of which encloses a separate slide valve 32 so that the simulated candles 16 may be of uniform height and supported on inclined supporting means.

It will thus be seen that a simple and efficient automatic candelabra has been disclosed which may be economically constructed of relatively simple parts and which will give the appearance of a conventional candelabra and wax candles both when ignited and when extinguished and that additionally the device provides for the automatic ignition of the several candles from a remote location at a predetermined time and lighting arrangement as well as for the automatic extinguishment of the candles from a remote location also at a predetermined time and predetermined arrangement if desired.

It will thus be seen that the several objects have been met by the automatic candelabra disclosed herein.

Having thus described my invention, what I claim is:

1. An automatic candelabra including a support member, at least one tubular cross piece and at least one simulated candle positioned thereon, an oil reservoir and a wick in the said simulated

candle and an electrical igniter in the simulated candle in proximity to the said wick, and a passageway communicating with the said cross piece and a vacuum pump in communication with the said cross piece, and a valve in said cross piece normally closing communication between the cross piece and the passageway.

2. An automatic candelabra including a support member, at least one tubular cross piece and at least one simulated candle positioned thereon, an oil reservoir and a wick in the said simulated candle and an electrical igniter in the simulated candle in proximity to the said wick, and a passageway in said candle communicating with the said cross piece, a valve in said cross piece normally closing communication between the cross piece and the passageway, and means for remotely actuating said valve whereby the candle may be extinguished.

3. An automatic candelabra including a support member, at least one tubular cross piece and at least one simulated candle positioned thereon, an oil reservoir and a wick in the said simulated candle and an electrical igniter in the simulated candle in proximity to the said wick, a power source and circuit wires connecting said igniter with said power source, and a passageway communicating with the said cross piece and a vacuum pump in communication between the cross piece and the passageway.

4. An automatic candelabra including a support member, at least one tubular cross piece and at least one simulated candle positioned thereon, an oil reservoir and a wick in the said simulated candle and an electrical igniter in the simulated candle in proximity to the said wick, a power source and circuit wires connecting said igniter with said power source, and a passageway communicating with the said cross piece and a vacuum pump in communication between the cross piece and the passageway, and means for remotely actuating said valve whereby the candle may be extinguished.

5. A candelabra comprising a tubular support member, a vacuum pump in communication with said support member, at least one tubular cross piece on said support member and in communication with the said support member, and a slide valve in said cross piece and remotely controlled means for actuating said slide valve, at least one simulated candle on said cross piece and a tube in said simulated candle communicating with the said cross piece, at least one orifice in the slide valve for registry with the said tube, a tip on said simulated candle defining an orifice, a wick tube positioned partially within said tube and a reservoir in said simulated candle about the said tube and electrical means for igniting the said wick, and electrically actuated means for moving the said slide valve.
